SHOE SOLE OR SHOE SOLE ELEMENT

Stanislav V'Soske, Grand Rapids, Mich.

Application December 26, 1942, Serial No. 470,127

9 Claims. (Cl. 36—25)

This invention relates to improvements in shoe soles or shoe sole elements.

The main objects of this invention are:

First, to provide a shoe sole or shoe sole element which has substantial wearing qualities, possesses a suitable rigidity and at the same time is formed without the use of leather or metal.

Second, to provide a shoe sole element having the above advantages which may be applied or associated with an upper by the use of machinery now widely in use without the necessity of substantial modification therein.

Third, to provide a shoe sole element which may be economically produced in large quantities.

Objects relating to details and economies of the invention will appear from the description to follow. The invention is defined in the claims.

A preferred embodiment of the invention is illustrated in the accompanying drawing, in which:

Fig. 1 is a fragmentary side elevation of my improved shoe sole element, its association with an upper and a heel being indicated by dotted lines.

Fig. 2 is a top plan view of my improved shoe sole element, parts being shown conventionally.

Fig. 3 is a bottom view, parts being shown conventionally.

Fig. 4 is an enlarged transverse section on line 4—4 of Fig. 3.

Fig. 5 is an enlarged longitudinal fragmentary section on line 5—5 of Fig. 2.

It should be understood that I use the term "shoe" in its broader meaning as including various kinds of footwear, such as boots, shoes, slippers, sandals, and the like.

The shoe sole of the embodiment of my invention illustrated comprises a foundation fabric 1 in which the warp and woof are of the same size multithread cord-like strands 2. These strands are preferably of cotton, the desirable feature of which for this use is the strength and the fact that it does not have objectionable stretching qualities.

The foundation fabric is firmly woven. To this fabric I apply strand-like nap material 3, the nap material being looped into the foundation fabric to provide a continuous nap of substantial depth and density as illustrated. The tufts of the nap are left uncut.

The nap loops 4 provide a substantially continuous tufted tread surface.

In the toe portion or area 6 the tufts are set in such density as to provide a closely compacted nap area, as shown in Fig. 5. This nap area

may be made more dense in the matter of the nap than the ball portion of the foot, as shown in Fig. 4.

The shank portion 7 is preferably made less dense than the ball portion. The main advantage in making it of less density is the saving in material. The dense toe portion, it will be understood is subject to greater wear than the ball portion.

10 The edges 8 of the foundation fabric are extended beyond the tufting while at the heel there is a heel portion 9 of foundation fabric only also extended beyond the tufting, see Fig. 3.

The tufting may for lighter shoes such as 15 women's shoes, be desirably formed of wool strands. When formed of wool strands, a braided welt strip 10 is secured to the foundation fabric by stitching at 11. This welt strip is placed around the tufting or at the edges of the nap tufting in supporting relation thereto, as shown in Fig. 4.

After the tufting and welt strip are applied, a layer or coating of waterproofing material 12, desirably of latex, is applied to the inner side 25 of the foundation fabric, this coating extending onto the untufted edges and desirably beyond the same as indicated at 13 in Fig. 2, the latex forming in itself a sheet-like layer.

A platform member 14 formed of relatively stiff 30 material, preferably fibrous material, is superimposed upon the foundation fabric and the untufted edges of the foundation fabric folded inwardly thereon. This provides a sole element which may be applied to the shoe in the usual 35 manner, the upper being indicated by dotted lines 15 and the heel by the dotted lines 16 in Fig. 1. A suitable insole and filler material can be superimposed on this wool element.

My improved sole element is, as stated, adapted 40 for a wide variety of uses and is found satisfactory for outdoor or general wear. The tufting may, if desired, be treated with waterproofing material. It is bound by the latex or waterproofing material so that in the event the loops wear through, the strands are still retained until the tufts are worn substantially down to the foundation fabric.

I have not attempted to illustrate or describe 50 the various embodiments or adaptations of my invention as it is believed that this disclosure will enable those skilled in the art to embody or adapt my invention as may be desired.

Having thus described my invention, what I 55 claim as new and desire to secure by Letters Patent is:

1. An outer sole comprising a woven foundation fabric in which both the warp and woof are of cord-like strands and including sole, shank and heel portions, strand nap material looped into said sole and shank portions of said foundation fabric in a predetermined sole tread and shank pattern and being uncut to provide a continuous tufted surface, the tufts being of substantial depth and uncut, the foundation fabric extending beyond the tufting and also beyond the heel portion of the foundation fabric, a welt strip disposed below the foundation fabric at the edges of the tufting and in side supporting relation thereto and stitched to the said foundation fabric, and a platform member of relatively stiff material superimposed on said foundation fabric and overlying the said sole, shank and heel portions thereof, the said extending portions of said foundation fabric being folded over the edges of and lapped upon the said platform member. 10
2. An outer sole for shoes comprising a foundation fabric having continuous sole, shank and heel portions, and tuft material looped into said foundation fabric in a predetermined pattern to provide a sole tread surface and a shank surface, the heel portion of said foundation fabric being without tufting, the foundation fabric having continuous portions extending beyond the edges of the tufted sole tread and shank portions and said heel portion, and a platform member of relatively stiff material conformed to and arranged upon the upper side of said sole, shank and heel portions of said foundation fabric, the said extending edges of said foundation fabric being folded inwardly into superimposed relation to said platform member. 15
3. An outer sole element comprising a foundation fabric and tufting material looped into said foundation fabric in a predetermined sole tread and shank pattern, the tufts being closely arranged in side by side mutually supporting relation, a welt strip of fibrous material disposed in surrounding side supporting relation to the border tufts and stitched to the foundation fabric, the foundation fabric being extended beyond the edges of the tufting and said welt strand, and a platform member arranged upon the foundation, the said extending edges of said foundation being folded inwardly into superimposed relation to said platform member and secured thereto. 20
4. An outer sole comprising a foundation fabric and tufting material looped into said foundation fabric in a predetermined sole tread pattern, the tufting being closely arranged in side by side mutually supporting relation, the foundation fabric being extended beyond the edges of the tufting, and a platform member arranged upon the foundation fabric, the said extending edges of said foundation fabric being folded inwardly into superimposed relation to said platform member. 25
5. An outer sole for shoes comprising a foundation fabric having integral sole, shank and heel portions surrounded by an integral border portion of substantial width extending beyond the edges of said sole, shank and heel portions, tuft material looped into the sole and shank portions of said foundation in predetermined sole and shank patterns to provide an outer sole tread surface 30 for the sole portion and an outer shank portion, the heel portion of said foundation being without tufting, said foundation border portion being also untufted and constituting means for anchoring the outer sole to associated shoe parts when 35 assembled therewith to present the tufted sole portion downwardly as a sole tread wear surface, and a cord of fibrous material of a diameter approximating the depth of the tufts disposed below the foundation at the edges of the tufts in side supporting relation thereto and stitched to the foundation, the tufts intermediate the said outer tufts being closely arranged in side by side supporting relation to each other. 40
6. A sole for shoes comprising a foundation fabric having integral sole, shank and heel portions surrounded by an integral border portion of substantial width extending beyond the edges of said sole, shank and heel portions, and tuft material looped into the sole and shank portions of said foundation in predetermined sole and shank patterns to provide an outer sole tread surface for the sole portion and an outer shank surface, the heel portion of said foundation being without tufting, said foundation border portion being also untufted and constituting means for anchoring the outer sole to associated shoe parts when assembled therewith to present the tufted sole portion downwardly as a sole tread wear surface. 45
7. A sole for shoes comprising a foundation having continuous sole, shank and heel portions surrounded by an integral border portion of substantial width extending beyond said sole, shank and heel portions, tuft material looped into the sole portion of said foundation in a predetermined sole pattern to provide an outer sole tread surface, said foundation border portion being untufted and of such width as to permit the turning thereof upwardly and inwardly for attachment to a superimposed shoe element when assembled in a shoe as an outer sole and to present the tufted sole portion downwardly to constitute a sole tread surface, the tufts being closely arranged in side by side supporting relation to each other and being uncut, and a cord of fibrous material of a diameter approximating the depth of the tufts disposed below the foundation at the juncture of the sole portion and the said border portion extending therefrom and stitched to the foundation in side supporting relation to the outer tufts. 50
8. A sole for shoes comprising a foundation having continuous sole, shank and heel portions surrounded by an integral border portion of substantial width extending beyond said sole, shank and heel portions, and tuft material looped into the sole portion of said foundation in a predetermined sole pattern to provide an outer sole tread surface, said foundation border portion being untufted and of such width as to permit the turning thereof upwardly and inwardly for attachment to a superimposed shoe element when assembled in a shoe as an outer sole and to present the tufted sole portion downwardly to constitute a sole tread surface. 55
9. A sole comprising a foundation fabric, tufting material looped into said foundation fabric in a predetermined sole tread pattern, the tufting being closely arranged in side by side mutually supporting relation, the foundation fabric being extended beyond the edges of the tufting to provide an integral border portion of substantial width, and a platform arranged upon said foundation fabric above the tufted sole portion thereof with the tufting facing downwardly to provide a sole tread surface, said border portion of said foundation fabric being folded inwardly and secured to said platform member. 60
